SKI BINDING

Louis Beerli, Engelberg, Switzerland

Application July 12, 1943, Serial No. 494,360
In Germany April 14, 1942

4 Claims. (Cl. 280—11.35)

This invention relates to ski bindings.

Ski bindings including heel straps are known in which forwardly of the toe irons two tightening levers are arranged which permit of adjusting the ski binding so as to exert decreased or increased tension. The same effect can be obtained by using a single tightener the means of which for engagement with the heel strap is provided with various rests in which the released tightening lever can be selectively inserted.

Further, ski bindings are known which are provided with two tightening levers arranged forwardly of toe irons and in which the heel strap is tightened by means of one tightening lever, whereas the other tightening lever serves for adjusting the position of a rearwardly disposed retaining means for producing or varying the diagonal tension, that is, connecting said retaining means with the heel strap or disconnecting same therefrom.

It has also already been proposed to arrange two oppositely displaceable claws on a rail which is displaceable longitudinally of a ski provided with a ski binding which is devoid of a heel strap and in which the toe irons can be shifted up and down in the vertical direction. These claws can function to engage with the sole of the boot at the narrowed portions thereof and when the rail is adjusted by a front tightener grasp the sole of the boot and pull the latter in between the toe irons. In this arrangement the rear end of the rail is provided with a nose which as the rail is shifted toward the front can be moved into engagement with a stationary guide fastened to the ski by which means rising of the heel of the boot from the ski is counteracted and a diagonal tension effect is obtained.

The ski binding, according to the present invention, which includes a tension member which is displaceable in the longitudinal direction of the ski and provided with parts adapted for producing or varying a heel depressing tension and for engaging with one or more abutment means that are fastened to the ski, and further a connection between a tightening lever and the tension member permitting of varying the tension exerted on the tension member by means of the tightening lever, is distinguished in that the parts for producing the heel depressing tension are adjustable by virtue of the influence of a spring.

Advantageously, the said connection is provided with means permitting of varying the tension acting upon the tension member instantaneously without readjustment of the tightening lever.

To this end the arrangement is, advantageously, such that the tension member is engaged with the abutment means when the tension is relatively great but is disengaged therefrom when the tension is relatively small or altogether ceased, so that in changing over to small tension or relief of tension the heel depressing tension is varied or ceased.

Two embodiments of the invention are illustrated in the accompanying drawing, by way of example only, in which

Fig. 1 shows a first embodiment of the invention in elevation;

Fig. 2 is a top plan view of Fig. 1 with the heel strap in the position of diagonal tensioning;

Fig. 3 is a like top plan view with the heel strap in position of walking with the skis;

Figs. 4 and 5 show an elevation and a top plan view respectively of a second embodiment of the invention;

Figs. 6 and 7 each show a sectional view of a detail with the latter in a different position, and Figs. 8 to 10 are views of modified details.

In the drawing the numeral 1 designates a ski having fixed toe irons 2. A tension member which provides a heel strap and is movable in the longitudinal direction of the ski is in the form of traction-transmitting means such as a flexible sole strap or rail 3 and consists preferably of a steel strip. This heel strap incorporates also a part 5 in the form of a cable and a heel engaging spring 4. At the rear end of the rail 3 a yoke 6 is secured which serves for producing a tension for depressing the heel on its seat hereinafter referred to as heel seating tension. The front ends of the cable portions 5 are anchored to the yoke 6 so that the latter is acted upon by the spring 4. The cable ends may be adjustably connected to the yoke 6 for the purpose of varying the length of the cable. On the top surface of the ski two hooks 6' are secured into which the yoke 6 can enter when the sole plate is shifted toward the front so that the hooks 6' serve as abutments for the sole plate to produce the heel seating tension.

The front end of the rail 3 is fastened to a member 7 which is displaceable longitudinally of a guide 8 which is secured to the ski forwardly of the toe irons 2. The member 7 is provided with two rests 9 and 10 which are arranged behind each other at different levels and are open in the downward direction (Figs. 6 and 7). A stirrup 11 of a tightening lever 12 which is fulcrumed on the guide 8 is selectively engageable with said rests for the purpose of exerting a rel-

atively strong or slight pull respectively. A push button 13 is associated with the stirrup 11. By placing the stirrup 11 into the rest 9 the front portion of the sole plate is shifted to such an extent that the heel engaging spring is strongly tensioned and thus a strong pull is exerted on the sole plate so that the yoke 6 comes to lie inside the hooks 6' (Fig. 2). In inserting the stirrup in the rest 10 the heel engaging spring is lightly loaded so that the tension set up in the sole plate is only slight.

By merely pressing down the button 13 by hand or by means of the ski pole the stirrup 10 can be pushed out of the rest 9 (Fig. 6), whereupon the member 7 is drawn rearward by action of the heel engaging spring 4 and the stirrup 11 seats in the rest 10. In consequence thereof the yoke 6 disengages from the abutments 6' (Fig. 3) so that it will be seen that the heel seating tension can be terminated abruptly without requiring the tightening lever 12 to be readjusted.

In its released condition the tightening lever 12 is turned over to the rear toward the toe irons 2 and the sole plate 3 is shifted toward the rear to such an extent that the heel engaging spring 4 is completely released so as to make the heel free. If then the tightening lever is operated for tightening the ski binding the rear end of the stirrup 11 moves into the rest 9 due to the stirrup 11 tending to share in the rotational movement by effect of friction intentionally produced between the front end of the stirrup and the tightening lever. In continuing the turning over of the tightening lever toward the front a strong tension is set up in the sole plate as previously referred to while this plate moves into engagement with the abutments 6' so that the sole plate 3 can be raised no longer and a diagonal tension is produced due to the inclined position assumed by the heel engaging spring 4 and the cable portions 5 which tension increases rapidly if the heel tends to rise from its seat.

The heel strap is then in position for starting to run downhill. If it is required to change over from this position for starting to run downhill into position for walking the exertion of pressure on the button as described above suffices for bringing about this condition in which the heel can be retracted from the ski with ease while the heel engaging spring remains stressed in an amount sufficing for retaining the boot in engagement with the toe irons.

If it is desired to retain the boot in position on the ski for walking while the tightening lever 12 is released the button 13 is depressed simultaneously with operating the tightening lever for exerting tension so that the stirrup 11 interengages with the rest 10.

Two flat bars 14 and 15 are firmly connected to the yoke 6, the bar 14 of which underlies the heel of the boot and is pressed down on the ski by the latter so that the yoke 6 being connected with this bar is also kept down for ensuring the reliable interengagement of the yoke with the abutments 6'. By action of the tension exerted on the yoke 6 by the cable 5 the latter is subjected to a torque tending to bend up the sole plate. This bending tendency is counteracted by the bar 14 as long as the latter is in bearing engagement with the heel of the boot. If, however, in the position for starting downhill the heel is raised from the ski the pressure exertion on the bar 14 closes. In this case the flat bar 15 is pressed down on the ski by action of the

torque referred to above so that the sole plate remains relieved.

In the position for starting downhill the sole is vigorously pressed in between the toe irons, whereas in the position for walking the pressure is greatly reduced for the reason that the heel engaging spring is relieved to some extent. This fact is of great advantage since the sole of the boot must be free for deflecting during the walking and must then be safeguarded against heavy pressures. Apart from this the friction between the sole of the boot and the side plates of the toe irons is greatly diminished and the movement relative to the latter considerably facilitated by the partial relief of loading of the heel engaging spring.

The embodiment shown in Figs. 4 and 5 differs from that precedingly described in that the sole plate is formed by a continuous cable loop 16 and an associated heel engaging spring 4. A cross member 17 which forms a part for producing the heel seating tension is firmly connected to the cable portions extending alongside of the ski on both sides thereof and engages firmly with an abutment 18 like the yoke 6 described in connection with the first embodiment. The cross member 17 is adjustable by virtue of the influence of the spring 4.

As shown in Figs. 8 and 9, a cross piece 23 may be provided with an orifice 21 having a slot 20 in its upper part corresponding in width to the thickness of the cable, and a thickening 22 provided on each lateral length of cable can be moved into and out of engagement with the walls of the orifice.

Further more than two rests may be provided in the member 7, for example, a series of four rests 9, 9', 9'' and 9''', as shown in Fig. 10, for obtaining a corresponding number of different conditions of relief of tension of the sole plate. One of these rests, for example the rest 9''', may correspond to the condition of complete relief of tension of this plate, so as to provide for a releasable binding in which the means for relieving the tension are controlled in any suitable manner usual for releasable bindings.

I claim:

1. A binding for holding a boot on a ski in two adjusted conditions comprising, toe irons 50 against which the toe portion of the boot engages in fixed position, a lever mounted on the ski forwardly of the toe irons and having a transversely extending pivot about which it is turnable, traction transmitting means extending rearwardly from the lever, a connection between said lever and said transmitting means including a plurality of differently located abutments and abutment-engaging means adapted to be selectively brought into engagement with either of the abutments for adjusting the traction, means including a spring for applying the traction to the heel of the boot in a forward and downward direction, the amount and direction of application of the traction depending on the position of the engaging means with respect to the abutments, and means operable while the ski is applied to the boot for shifting the engaging means from one abutment to the other without operating the lever.

2. A binding for holding a boot on a ski in two adjusted conditions comprising, toe irons 70 against which the toe portion of the boot engages in fixed position, a lever mounted on the ski forwardly of the toe irons and having a transversely extending pivot about which it is turnable, traction transmitting means extending rear-

wardly from the lever, a connection between said lever and said transmitting means including a plurality of differently located abutments and a stirrup swingably connected with the lever adapted to be selectively brought into engagement with one or another of the abutments for adjusting the traction, means including a spring for applying the traction to the heel of the boot in a forward and downward direction, the amount and direction of application of the traction depending on the position of the stirrup with respect to the abutments, and means operable while the ski is applied to the boot for shifting said stirrup from one abutment to the other without operating said lever.

3. A binding for holding a boot on a ski in two adjusted conditions comprising, toe irons against which the toe portion of the boot engages in fixed position, a lever mounted on the ski forwardly of the toe irons and having a transversely extending pivot about which it is turnable, traction transmitting means extending rearwardly from the lever, a connection between said lever and said transmitting means including a plurality of differently located abutments and a stirrup swingably connected with the lever adapted to be selectively brought into engagement with either of the abutments for adjusting the traction, means including a spring for applying the traction to the heel of the boot in a forward and downward direction, the amount and direction of application of the traction depending on the position of the stirrup with respect to the abut-

ments, and a button connected with said stirrup for operation to quickly release the stirrup from an abutment to alter the condition of attachment of the boot on the ski.

4. A ski binding for holding a boot on a ski in two adjusted conditions comprising, toe irons against which the toe portion of the boot engages in fixed position, a lever mounted on the ski forwardly of the toe irons and having a transversely extending pivot about which it is turnable, traction transmitting means extending rearwardly from the lever, a connection between said lever and said transmitting means including a plurality of differently located abutments and a stirrup swingably connected with the lever adapted to be selectively brought into engagement with either of the abutments for adjusting the traction, means including a spring for applying the traction to the heel of the boot in a forward and downward direction, the amount and direction of application of the traction depending on the position of the stirrup, means connected with said stirrup for operation to quickly release the stirrup from an abutment, a yoke connected with the traction transmitting means in rear of the toe irons, yoke-engaging means for holding the yoke and traction transmitting means close to the ski when one abutment is engaged by the abutment-engaging means, and for releasing the yoke when said abutment is not engaged by the abutment-engaging means.
